MOUNTING MEANS FOR THE FIXED IRONING ELEMENT OF IRONING MACHINES

Herman A. Sperlich, Detroit, Mich.

Original application September 13, 1941, Serial No. 410,709. Divided and this application April 17, 1944, Serial No. 531,411

1 Claim. (Cl. 38—58)

1

The present invention relates to ironing machines and particularly to that type of ironer of small size and weight adapted to be used on a table or other support and stored when not in use.

Among the objects of the invention is to provide mounting means for the fixed element of the roll and shoe combination capable of allowing easy and quick alignment of these parts.

Other objects and advantages will readily occur to those skilled in the art upon reference to the following description and the accompanying drawings in which:

Figure 1 is a rear view of the machine with the housing cover plate removed.

Figure 2 is an end view with a section of the housing and mechanism on line 2—2 of Figure 1.

Figure 3 is a perspective view of the roll and rotation control.

Figure 4 is a partial sectional view on line 4—4 of Figure 1.

Figure 5 is a front elevation of the roll control mechanism shown in Fig. 4.

Figure 6 is a longitudinal section through the roll and supporting yoke.

Figure 7 is an enlargement of a portion of Figure 6 but with the parts in another position.

Fig. 8 is a more or less diagrammatic view showing the storage of the cord in the base.

Figures 9 and 10 are respectively a right and left hand end view of the air directing element shown in Figure 6.

Figures 11, 12 and 13 are details of the construction of the ironing shoe mounting on an enlarged scale.

In the drawings, the machine is shown as comprising a base 10, preferably hollow and having an opening for receiving an electric cord or cable 17 for supplying electricity to the roll motor and ironing shoe.

Upon the base, and secured thereto or integral therewith is a pair of pedestals 11 and 12 located at or near the longitudinal center of the base—one at the front and one at the back of the base 10, so as to provide a U-shaped frame. The pedestal 11 is hollow or has suitable conduits therein for electric conductors leading to the shoe 13 mounted thereon and also carries a suitable switch 14 and light signal 15. In front of the

shoe 13 and also carried by the pedestal 11 is a feed board or platform 16.

The roll 20 is mounted for rotation between the arms of a yoke 21 formed of tubing or its equivalent, and yoke 21 being carried by the pedestal 12, passing through and having bearings in the side walls thereof, while within the pedestal is mounted the mechanism by means of which the roll, through swinging of the yoke, is moved against or away from the shoe 13.

The mechanism referred to is shown most clearly in Figures 1 to 3 to comprise two arms or rods 25 fixed to the horizontal part 21a of the yoke and extending backward a short distance, which arms lie in channels 26 extending along the lateral edges of a plate 27, the forward edge of which is provided with a laterally arranged channel 28 in which is seated the yoke member 21a.

Overlying plate 27 and arms 25 is a second plate 30 having fixed at its center a depending rod 31 passing loosely through plate 27 and provided with a head or head plates 32 between which and the plate 27 is a stiff coil spring 33 serving to hold resiliently together the two plates 27 and 30. The plate 30 has pivoted at each end a link 35 extending downwardly and forming part of a toggle, the other link of which consists of a yoke 36, itself pivoted at 37 in the side walls of the pedestal 12.

Anchored within the base of pedestal 12 is a tension spring 40 which, through a suitable link 41, is connected to the plate 30, and since the links of the toggle 35—36 are so arranged that, in either position of the roll, they are past center, this spring 40 serves to hold the roll in position.

Operation of the toggle 35—36 and thereby the roll is accomplished through the lever 140 fixed to the yoke member 36 and extending from the top of pedestal 12 through a suitable slot 19. In order to strengthen the anchorage of lever 18 to member 36, a suitable brace 22 in the form of a stirrup is secured to the under side of the cross piece of member 36 and the end of lever 18 secured thereto, the lever passing through a suitable opening in the cross piece.

The rotation of the roll is most conveniently accomplished by means of an electric motor housed within the roll itself and supplied with current by conductors leading thereto through

one of the hollow arms of yoke 21, and the circuit is controlled by means of a suitable switch 46 mounted on yoke 36 and whose operating lever 47 is spring biased to closed circuit position. This lever 47 lies in the path of movement of a lever 148 pivoted upon the brace member as at 148a, and has its free end below the switch lever 47.

Below the lever 148 is a plate 150 provided with a portion extending under the lever 148 and formed with an inverted V-shaped portion 150a, normally lying in a notch in the under edge of lever 148. This plate is fixed to the end of the lever 140. Rotary movement, therefore of lever 140, through the action of the V-shaped portion 150a and the notched lever 148, will lift the switch lever 47 to open circuit position. With this construction, the motor may be kept idle or stopped when the roll is down, by merely rotating the lever 140 to one side or the other.

As stated above, in the present machine, the motor is mounted in the roll and this construction is shown best in Figures 6 to 10.

In these figures, the roll 20 is shown as hollow and carried on suitable bearings 60 on the arms of yoke 21. These arms are likewise hollow and one of them, 21b, is provided with an extension 21c projecting into the roll and secured to a spider 61, the arms of which extend for a short distance lengthwise of the roll and are fixed to a suitable clamping ring 62 which embraces and supports one end of the motor 63. The motor 63 has at its other end a suitable reduction gearing 64 from which extends a driving shaft 65 carrying at its end a thimble 66 fixed thereto by the pin 67 and having a suitable bearing such as the antifriction bearing 68, within the end of the yoke arm 21d. This thimble 66 forms a part of a clutch mechanism adapted to connect and disconnect the roll 20 from the motor drive.

The clutch comprises the thimble 66 which is provided with a plurality of radial holes for the balls 70 which in their outward position cooperate with notches in a ring 71 fixed to the end plate 72 of the roll 20, but, in their inner position, allow the roll to turn freely about the thimble. These balls 70 are moved outwardly to driving position by the circular cam 75, thrust outwardly by the spring 78, which cam is provided with a pin 76 extending through the end of thimble 66 into the yoke arm 21d, while mounted within the latter is a lever 79 adapted to push inwardly the cam 75 and allow the balls 70 to drop into their holes in the thimble 66 and thus release the roll.

In order to prevent the balls flying out under centrifugal action when not being urged out by the cam, a suitable spring 80 is mounted on the thimble 66 in such fashion as to press the balls inwardly when the cam 75 has moved from behind them.

The lever 79 is actuated by a rod 85 mounted in the horizontal portion 21a of the yoke 21 and this rod is in turn moved longitudinally by one arm of a bell crank 86 pivoted under the plate 27, the other arm having a downward extension 87 arranged to coact with a pin 88, which pin may be one of the hinge pins for the yoke member 36. The arrangement provides for the actuation of the roll clutch whenever the roll is lifted or lowered. When the roll is lifted, the pin 88 swings toward the crank 86 and moves rod 85 toward the right (Figure 6) swinging lever 79 to move the cam 75 to ball release position. When the roll is lowered, the reverse action of these parts clutches the roll to the motor drive shaft 65.

In order to prevent overheating of motor 63 it is preferably well spaced from the roll shell and provided with air forcing and directing means for blowing thereover a considerable volume of air. This cooling means consists of a fan 90 at the end of the motor within the spider 61, together with a cup member 91 having a central opening 92 and slots 93 for the passage of the arms of spider 61 which latter serve not only as motor supporting means, but as means for directing air from the fan along the walls of the motor.

The cup 91 serves to turn longitudinally of the motor all of the air projected radially by the fan. The air is admitted and allowed to exit through suitable holes 95 in the ends 72 of the roll.

In Figure 10 there is shown more or less diagrammatically the use of the hollow base 10 as a storage means for the excess length of conductor 17 when the machine is in use or of all of it when the machine is to be idle or stored. In this figure, the conductor 17 is shown as connected to a suitable connecting block 17a some distance from the opening 17b through which the conductor enters the base. From this block, connections may be made to the shoe 13 and motor 63. The distance between block 17a and opening 17b permits the thrusting of the conductor into the hollow base as shown.

In Figures 11 to 13 there is shown a feature of construction permitting the easy adjustment of the ironing shoe 13 to provide proper alignment of the shoe 13 and roll 20. In these figures, the frame 10-11-12 is shown as made of two side members 11a and 11b fixed by welding or otherwise to a filler or spacer plate 11c, these three parts forming the sides and inner surface of the U-shaped frame.

At the upper ends of the members 11a and 11b adjacent the ironing shoe 13, are provided the outwardly extending ears 111, perforated for the passage of bolts 112. At the back face of shoe 13, the heating element (not shown) is enclosed in a tray 113 fixed to the shoe and supported upon the upper end of the pedestal 11 formed with the ears 111.

At the central portion of tray 113 are formed two curved surfaces 114 so formed as to be portions of a sphere, while the ears 111 are correspondingly curved and spaced.

When the bolts 112 passing through these curved surfaces are loosened and the roll 20 lowered upon the shoe 13, these two parts are automatically aligned and may be fixed in such adjusted position merely by tightening the bolts 112.

The part 120 is a shield over the tray 113.

This application is a division of application Serial No. 410,709, filed September 13, 1941 now abandoned.

Now having described the invention and the preferred embodiment thereof, it is to be understood that said invention is to be limited, not by the specific details herein set forth, but only by the scope of the claim which follows:

I claim:

In an ironing machine having an ironing shoe and a rotatable roll, one of which elements is fixed in position and the other of which is movable toward and from the fixed element, means for mounting the fixed element comprising a support member having at its upper end a spherical cup formation, means on said fixed element adapted to mate with said cup formation, said

mating portions being provided with slotted openings, and bolts loosely fitted in said openings and adapted to fix said portions in adjusted position.

HERMAN A. SPERLICH.
